UNITED STATES PATENT OFFICE.

FRANK MASHAK, OF NEWARK, NEW JERSEY.

BOOKMARK.

Application filed August 31, 1927. Serial No. 216,743.

The present invention relates to a book mark, and aims to provide a novel and improved device of this character which may be conveniently attached to a page of a book in 5 an efficient manner so as to indicate the page a party left off reading in order to continue reading the book.

Another object of the invention is the provision of a book mark arranged in the form 10 of a clip to be attached to a page of a book in a manner so as not to mar or mutilate the page, as well as a book mark which will project but slightly beyond the pages of a book so as to have a neat appearance, yet readily 15 indicate in a conspicuous manner a place in the book.

It is also an object of the invention to provide a device of the above indicated character, 20 which is simple and substantial in construction, which can be manufactured economically, and which will be thoroughly efficient and practical in use.

With the foregoing and other objects in view, which will be apparent as the description 25 proceeds, the invention resides in the construction and arrangement of parts, as hereinafter described and claimed, it being understood that changes can be made within the scope of what is claimed, without departing 30 from the spirit of the invention.

The invention is illustrated in the accompanying drawings, wherein:

Figure 1 is a fragmentary plan of a book 35 shown in open position with my improved book mark applied to a page thereof,

Figure 2 is a plan of the mark,

Figure 3 is an edge elevation of the same, and

Figure 4 is a cross section taken on line 4—4 40 of Figure 1.

In carrying out the invention I employ a strand of wire 10 which is bent back upon itself intermediate its ends so as to provide a pair of parallel bars 11 which form a tongue 45 12. The bars 11 are bowed, as at 13, after extending parallel to each other for a substantial distance, and are then twisted upon each other, as at 14. The strand of wire after being twisted has its opposite ends directed 50 away from each other, as at 15, then extended downwardly, as at 16, in parallel spaced relation, and then the end 17 of the strand extends across, beneath the point where the strand of wire was bent upon itself to form 55 the tongue 12, and is attached to the other end of the strand at the point 18. By referring to

Figure 2 of the drawings, it can be seen that after the tongue 12 is formed with the bowed portion 13 therein and the strand twisted upon itself, as at 14, the ends of the wire from a rectangular frame arranged about the tongue. The end of the tongue is adapted to engage the end of the rectangular frame, opposite that to which it is connected as at 19.

After the strand of wire has been in this shape it is flattened by stamping or running the same between a pair of rollers to shape the wire oblong in cross section, as clearly shown in Figure 4 of the drawings. By flattening the wire, the same will take up a minimum amount of space between the pages of a book so as to practically leave no openings between the pages of a book where the mark is arranged, as well as preventing the pressing of the strands of wire into the pages when the book is in closed position and subjected to pressure. By spacing the side portions 16 of the frame of the book mark from the tongue 12, it can be seen that the page of the book placed between the tongue and frame, as shown in Figure 1 of the drawings, is not subjected to sharp bends which would tend to mutilate the page. As the book mark is made of tempered metal, the tongue will always remain in the proper position independent of the fact that several pages or thick pages of a book have been held between the tongue and frame of the device. The bowed or yielding portion 13 will allow the tongue 12 to be easily moved away from the portion 17 of the frame so as to permit the book mark to be readily slid upon the opposite sides of a page of a book.

When the book mark engages a page of the book, the portions 15 are the only parts that project beyond the edge of the book, whereby the appearance of the latter is not affected and yet the mark is sufficiently conspicuous to be seen when it is desired to locate a portion of the book which has been indicated by the placing of the book mark on a page thereof. When the book mark is removed it is not distorted or otherwise injured and being constructed of durable metal it can be used an indefinite number of times.

Having thus described my invention, what I claim as new is:

1. A book mark made from a single strand of wire bent upon itself to form a tongue with oppositely bowed portions at the inner end thereof beyond which the wire is twisted together, and a frame cooperating with the

tongue and extending around the same at a distance from opposite sides thereof, the portions of the wire at one end of the frame extending in opposite directions from the inner 5 end of the tongue.

2. A book mark comprising a strand of wire bent intermediate its ends to provide a longitudinal tongue, said strand being bowed and twisted together at the end of the bowed 10 portion, the strand being bent into a rectangular frame about the tongue with the lower portion of the frame in engagement with the end of the tongue.

3. A book mark comprising a strand of wire bent intermediate its ends to provide a longitudinal tongue, said strand being bowed and twisted together at the end of the bowed portion, the strand being bent into a rectangular frame about the tongue with the lower portion of the frame in engagement with the 15 end of the tongue and the side portions at one side thereof, said side portions of the frame being spaced considerable distances from the tongue. 20

FRANK MASHAK.
